2 SHEETS-SHEET 2

Inventor
J. R. Baumann,
By *Franklin J. Baumann*,
Attorney

UNITED STATES PATENT OFFICE.

JOHN R. BAUMANN, OF RED WING, MINNESOTA.

RAIL JOINT.

Application filed September 27, 1921. Serial No. 503,603.

To all whom it may concern:

Be it known that I, JOHN R. BAUMANN, a citizen of the United States, residing at Red Wing, in the county of Goodhue and State of Minnesota, have invented certain new and useful Improvements in Rail Joints; and I do hereby declare the following to be a full, clear, and exact description of the invention, such as will enable others skilled in the art to which it appertains to make and use the same.

This invention relates to a rail joint of spliced shoe construction.

The main objects are to provide a novel and improved construction giving a practically perfect expansion joint so that the rails may contract and expand with ease; one in which the use of bolts is avoided; one having a connector holding both rails in place and strengthening the joint between them; one in which the connector forms part of the rail and avoids the knocks as a wheel passes from one rail to another in continuity as practically a single rail; one that securely locks and holds the connector in place; a shoe that gives bearing strength to both rail ends; a connector that is easily fitted and applied readily as by a sliding bottom plate and such a construction as will be less expensive than the usual fish plates and bolts.

Additional objects and advantages will appear hereinafter, the description to be taken in connection with accompanying drawings illustrating one practical embodiment.

In said drawings:—

Figure 1 is a plan view of rails connected by means of my improved structure;

Figure 2 is a side elevation of the parts of Figure 1;

Figure 3 is a cross section on the line 2—2 of Figure 1;

Figure 4 is a detail perspective view illustrating one end of a rail to be joined by my improvement;

Figure 5 is a detail perspective view of one end of my improved splicing connector and chair-plate associated therewith.

Throughout the views, like reference characters designate corresponding or similar parts.

Referring specifically to the drawings, a chair plate 7 is provided to mount meeting ends of adjacent rails 8, and a splicing connector 9 for said ends.

Splicing connector 9 has a tread flange 10 corresponding to and alining with the tread flanges of the rails 8 at 11. Depending walls or webs 12 are formed integral with the tread 10 and spaced from each other at 13. Extending laterally and downwardly, integral with the walls 12, are base flanges or walls, which have depending ribs 15 integral therewith. This connector 9 is independent of chair plate 7.

On the chair plate 7, ribs 15 rest. Flanges 16, preferably integral with the plate 7, rise therefrom and terminate in hook ends 17, which overlap ribs 15 and flanges 14 to prevent relative vertical movement of the plate 7 and connector 9.

As shown at 18, both ends of one wall 12 extend beyond the ends of the other wall 12 and the rib 15 carried by the first wall 75 extends in like manner beyond the rib carried by the second or shortened wall. The tread 10 is cut away flush with the inner surface of the web or wall 12 of greater length.

The rails in the main, are of standard construction, involving in addition to the said tread flanges 11, webs 19 and base flanges 20. Tread flanges are cut away at 21, so as to interengage with the ends of the tread 10 of the connector.

In use, the rails 8 being in proper proximity, and the connector being detached from the plate 7, such connector may be coupled with the rail end by vertical movement. The connector is forced downwardly so that the adjacent web flanges 19 of the rails will be received in the space 13 at the ends of the tread, and flanges 10 and 11 will interlock as shown in the drawings. By 95 longitudinal sliding movement, below the rails, chair plate 7 may then be positioned, so that the flanges 17 will overlap flanges 14 and thus prevent vertical displacement of the chair plate and connector or relative 100 vertical movement thereof.

If desired, of course, plate 7 may be attached to the connector before the rails are secured to the connector, in which event, the rails are by longitudinal sliding movement 105 disposed so that the webs 19 enter the spaces 13 and the tread flanges 10 and 11 interlock as in the previous instance.

It is to be borne in mind, that the rails are of standard construction, aside from the cutting away of the tread flange at 21 and 22. In view of this fact, the rails may in-

itially be manufactured of this shape or when desired, ordinary rails, by means of a hack saw, for instance, can have a portion of the tread flange thereof moved, so as 5 to conform to the shape of the rails 8.

Changes may be resorted to within the spirit and scope of the invention.

What is claimed is:—

1. A rail joint comprising a connector 10 having a tread portion, spaced depending webs carried by said portion, adjacent rail ends having their tread flanges cut away and adapted to have their web portions received between the spaced webs of the connector, 15 said tread flange of the connector having a cut away portions, said connector adapted to have its tread portion longitudinally overlap and rest on the upper edges of the rail webs at the rail ends, and to have its 20 cut away portions overlap longitudinally the tread flanges of the rails.
2. A joint for rails comprising a connector, a tread flange on the connector to aline with the tread flanges of the rails, 25 spaced webs depending from the tread of the connector, base flanges extending from

said webs, ribs depending from said base flanges, said connector at its ends having cutaway portions, the webs of the adjacent rail ends being disposable intermediate said 30 webs of the connector, the base flanges of the adjacent rail ends being disposable in the space below the base flanges of the connector, the tread flanges of the adjacent rail ends being cut away to overlap longitudinally 35 with the tread flange of the connector, a chair on which the adjacent ends of the rails rest, said ribs resting on said chair adjacent the longitudinal edges of said base flanges, said chair having upstanding flanges, and hooked ends extending inwardly from said flanges to overlap the base flanges and ribs carried thereby, whereby to prevent relative vertical movement of said connector and said chair. 40 45

In testimony whereof I affix my signature in presence of two witnesses.

JOHN R. BAUMANN.
